US0D1081431S

(12) **United States Design Patent** (10) **Patent No.:** **US D1,081,431 S**
(45) **Date of Patent:** **** Jul. 1, 2025**

(54) **DOOR OR WINDOW MAGNETIC SENSOR**

(71) Applicant: **Hangzhou Ezziv Software Co., Ltd.,**
Zhejiang (CN)

(72) Inventors: **Chongkun Huang**, Zhejiang (CN);
Weike Zhu, Zhejiang (CN)

(73) Assignee: **Hangzhou Ezziv Software Co., Ltd.,**
Zhejiang (CN)

(**) Term: **15 Years**

(21) Appl. No.: **29/892,416**

(22) Filed: **May 17, 2023**

Related U.S. Application Data

(62) Division of application No. 29/782,896, filed on May 10, 2021, now Pat. No. Des. 996,250.

(57) **CLAIM**

The ornamental design for a door or window magnetic sensor, as shown and described.

DESCRIPTION

FIG. 1 is a front elevation view according to the present design;

FIG. 2 is a back elevation view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1; and,

FIG. 7 is a perspective view of FIG. 1.
